UNITED STATES PATENT OFFICE.

VALLEY VIRGIL PEONE, OF CHEWELAH, WASHINGTON.

TRACTION ENGINE.

1,416,379.

Specification of Letters Patent. Patented May 16, 1922.

Application filed September 8, 1920. Serial No. 406,953.

To all whom it may concern:

Be it known that I, VALLEY VIRGIL PEONE, a citizen of the United States, residing at Chewelah, in the county of Stevens and State 5 of Washington, have invented a new and useful Traction Engine, of which the following is a specification.

My invention has reference to improvements in traction engines and it consists essentially in the peculiar features of construction and novel combination of parts 10 fully explained in the following detailed description, specifically pointed out in the appended claims and illustrated in the accompanying drawings, in which:

Figure 1 is a side elevation of my improved construction of traction engine.

Figure 2 is a plan view of the front portion thereof, the friction pinions that control 20 the shifting of the treads to the raised and lowered positions being shown out of gear with the main friction or driving wheel.

Figure 3 is a detail plan, one of the friction pinions being shown in operative connection with the driving wheel.

Figure 4 is a horizontal section taken on the line 4—4 on Figure 5.

Figure 5 is a transverse section of my improved traction engine, taken on the line 30 5—5 on Figure 1.

Figure 6 is a detail sectional view herein-after referred to.

A serious fault in traction engines of the endless track type is the excessive power loss 35 while making turns, namely by reason of the tendency of the treads sliding or skidding around, when turning, it being well known to those skilled in the art to which my invention relates, that, when swerving 40 from a straight course, there is caused a skidding of one or the other of the endless trackways, depending upon the direction of the swinging movement, thereby materially reducing the traction power of the engine.

Again, in some forms of tractor engines 45 of the endless track type, the direct stresses or reversal of stresses are frequently such that they result in breaking and disarrangement of the parts and at inconvenient times.

My invention primarily has for its object 50 to provide an improved construction of traction engine of the type before mentioned, in which the parts are more especially designed and cooperatively arranged for being driven 55 with the ordinary differential or transmission gears, such as are used in the ordinary

engine driven tractor, whereby skidding action or dragging of the endless track members is prevented and which also provides for making a quicker turn in a shorter space 60 than has heretofore been done and, at the same time, dispensing with the need of drive gearing such as is used on the common types of tractor engines now in use.

Referring again to the drawings, in which 65 like numerals indicate like parts in all of the figures, 1—1 designates the horizontal or bed beams of the frame or chassis.

In my construction, the forward ends of the beams 1 are joined by a cross beam 2 on 70 which, midway its ends, is mounted a turn table or member 3 that is joined with the beam 2 by a king or stud bolt 4 that is fixedly connected with the turn table 3 and journals in a vertical bearing aperture 2^a in the cross beam 2, with the upper end thereof shaped for receiving a suitable turning crank 4^a, which, in practice, is connected with any suitable actuating means operable from the driver's seat 5, mounted on a rear cross beam 6, 80 the latter being supported on the rear ends of the endless treads, as is clearly indicated in Figure 1, and as presently more fully described.

As is best shown in Figure 5, the side 85 beams 1 are I-shaped in cross section and, at a suitable point near their forward ends, the said beams support a cross beam 7 whose ends are secured to the I beams 1 by lag bolts 8—8, as shown in the detail view Figure 90 6 and, at each end, the said cross beam 7 is equipped with a pocket or thrust bearing 9—9, each of which has a pocket or concavity 90—90 on the upper face that constitutes the seat or bearing for the lower end 11 of a lifting or jack screw 10, the upper ends of which engage upper thrust or pocket bearing castings 12—12, secured one on each of the opposite ends of a cross head or beam 13 that is bolted down to a pair of uprights 14—14 100 which constitute guides for a lifter beam, the purpose of which will presently appear.

The lower ends of the uprights 14—14 are supported upon and bolted to the cross beam 7, as is clearly indicated on Figure 5.

At a point adjacent to and at the rear of the jack screws 10—10, a pocket thrust bearing 16 is fixedly bolted or otherwise secured upon the upper face of each of the opposite side beams 1 and each of the said bearings has a pocket or seat, the said two bearings 16—16 being oppositely dis-

posed for receiving the end journals of a driven shaft 17 to which motion is imparted, at desired times, in either direction, from the motor engine 18.

5 By referring now more particularly to Figure 2, it will be observed that the engine shaft carries a fly wheel, which, in my construction of tractor engine, constitutes a main friction drive 20, it being bevelled and 10 so disposed with respect to the driven shaft 17, that it cooperates with a pair of oppositely disposed friction clutch pinions 19-19 that slidably engage but are rotatable with the shaft 17, it being understood 15 that, when one of the pinions 19 is moved into gear with the main drive 20, the shaft 17 is driven in one direction and, when the other one of the said pinions 19 is thrown 20 into mesh with the main or engine drive 20, the first mentioned pinion being out of mesh, the shaft is driven in opposite direction, the reason for which will presently appear.

21 designates a cross or foot bar that is located adjacent the driver's seat and is secured, at its ends, to the top of the opposite side beam 1.

On the bar 21 is pivotally mounted a pair of foot levers 22-22, each of which joins 30 with an individual connecting rod 23, the rod, at one side, pivotally joining with a bevelled crank lever 24, which includes a straddle member 25 that takes into the grooved collar 26 on the clutch pinion 19 35 at the adjacent end of the shaft 17, the other rod 23 being likewise connected with the other clutch pinion 19, as shown, and the foot controlled devices are so arranged that the driver may readily shift either of the pinions 19 into mesh with the main drive 20 or move either of the pinions out of mesh with the said main drive, when it is desired to stop adjustment of the endless tread or track member.

40 At each of the opposite ends, the driven shaft 17 has a worm gear 27-27 and the said worm gears 27-27 each mesh with a worm gear 28 mounted upon an adjacent jack screw, the worm gear connections joining the jack screws and the engine drive being located at the lower end of each of the 45 said jack screws, as is best shown in Figure 2.

50 30-30 designate stay braces that take over the upper bearings for the jack screws and extend lengthwise of the beams 1 and are bolted, at their ends, to the said beams, as shown.

55 31 denotes a supplemental front I-beam, hereinafter termed the tractor treads lifting beam, and the said beam, in the practical adjustment of the parts, is guided in its up and down movements by the uprights 60 14-14, before mentioned, upon which the beam 31 rides in its up and down movement, such engagement of the beam and the up-

rights being provided for by the peculiar connection of the beam with the endless treads, as presently explained.

The lifter beam 31 is provided with a pair of screw nuts 32-32, one for each jack screw, which latter work through the said nuts 32 for raising and lowering the beams according to the direction or motion imparted to the said jack screw.

At the outer ends, the beam 31 is longitudinally recessed on the under side, as at 75 33-33, and in each of the said recesses 33 is mounted a horizontal shaft or rod 34-34, on each of which is pendently and swingably suspended a pair of hangers 35-35 between 80 which the upper ends of the opposite treads are sustained.

85 Each of the treads referred to consists of an endless track comprising a series of flexibly connected members 37 that pass over front and rear polygonal disks 38-39, the rear ones 39 of which are mounted on a transverse rear axle 39 which is journaled in bearings 39^b pendent from the under side 90 of the side beams 1-1, as is clearly shown in Figures 1 and 5 of the drawings.

The portions of the axle 39^a that project beyond the pendent bearings 39^b constitute the rear supports for side members 42 between which roller bearings 43-43 are supported and over which the upper and lower slack portions of the flexible endless track 37 pass, as is clearly illustrated in Figure 1.

95 The upper or front ends of the frame or side members 42-42 are supported by individual cross rods 34, which rods are mounted on the opposite ends of the lifter beam 31, as is best shown in Figure 5, by reference to which it will be seen in each pair of hangers 35, suspended from the rods 34, is journaled a short shaft 38^a and on each shaft 38^a is mounted a front polygonal disk 38 over which the endless track 37 passes.

100 To prevent slipping, the steering wheel is formed with an annular flange 43, as shown.

110 From the foregoing description taken in connection with the drawings, the complete construction, the manner in which the parts may be adjusted and the advantages of my invention will be readily apparent to those familiar with the making and using of machines of the type described.

115 To lift the endless tread, one of the clutch pinions 19, depending on the direction in which the tractor may be traveling, through the medium of the foot controlled devices, is moved into mesh with the main drive 20, and thereby imparts rotation to the shaft 17 and through the worm gears 27-27 transmits rotation to the gears 28 on the jack screws 10-10 that elevate the beam 31, it being apparent by referring to Figure 5 of the drawings, the connection of the beam 31 with the screws 10-10 and the uprights 14-14, is such that the said beam is 120 evenly guided in its vertical adjustment.

By flexibly supporting the front end of the endless tread carrying frame from the lifting beam 31, as stated and shown, binding of the said front ends of the endless tread carrying frame is avoided.

The front or steering wheel, which constitutes the forward support for the tractor, acts to avoid slipping, when steering, and thereby does away with the danger of the tread sliding around.

Furthermore, by providing for lifting practically the entire tread surface of the endless treads, other than their rear end supports, the entire tractor can be turned around much quicker and with greater ease and in much shorter space than is possible with the ordinary types of engine tractors now in general use.

While the detailed arrangement of the parts, as shown and described, presents a practical and preferred construction of my invention, it is to be understood that I do not confine myself to the exact detailed arrangement shown and described, as the said parts mentioned may be varied or modified to suit the particular condition that may be required in a complete development of my improved tractor engine, without departing from my invention as set out in the appended claims:

What I claim is:

1. In an engine equipped tractor of the character described, the combination with the tractor frame, the said frame including a bottom cross beam, uprights rigidly mounted on the said bottom cross beam and a cross head rigidly sustained on the upper ends of the said uprights; of a pair of oppositely disposed vertical jack screws one for each side of the machine whose lower ends travel in the bottom cross beam and whose upper ends travel in the cross head, an endless track mechanism located at each side of the tractor frame, means for mounting the rear end of the tractor frame and the endless treads so that the rear ends of the treads constitute the rear support for the tractor frame; a rotary support for the front end of each endless tread, mechanism on the tractor for raising and lowering the front ends of the endless treads, the said mechanism including a cross beam located above the tractor frame, the said beam having internally threaded bearings for engaging the jack screws, and guide apertures for engaging the fixed uprights and power transmission operable from the engine and including drive gears engaging the jack screws for applying rotation to the said screws for raising and lowering the cross beam and

hanger devices on the opposite ends of the said cross beam that sustain the front ends of the endless treads at their respective ends.

2. In an engine equipped tractor of the character described, wherein is provided a main frame, a steering wheel support at the front of the main frame and an axle provided with disks at the rear of the frame, beams pivoted to said axle and extending forwardly at each side of the main frame, disks carried by said beams and an endless tractor tread passed around the last named disks and the first named disks; a means for raising and lowering the front ends of said beams, said means comprising vertical standards mounted on the main frame, a cross head connecting said standards, screws journaled in bearings on the main frame and in the cross head, a vertically adjustable cross beam slidable on said standards and engaged by said screws, links connecting said cross beam with said pivoted beams whereby as said cross beam is raised and lowered, said pivoted beams will be raised and lowered, and engine driven means connected with said screws for actuating the same.

3. In an engine equipped tractor of the character described, wherein is provided a main frame, a steering wheel support at the front of the main frame and an axle provided with disks at the rear of the frame, beams pivoted to said axle and extending forwardly at each side of the main frame, disks carried by said beams and an endless tractor tread passed around the last named disks and the first named disks, a means for raising and lowering the front ends of said beams, said means comprising vertical standards mounted on the main frame, a cross head connecting said standards, screws journaled in bearings on the main frame and in the cross head, a vertically adjustable cross beam slidable on said standards and engaged by said screws, links connecting said cross beam with said pivoted beams whereby as said cross beam is raised and lowered, said pivoted beams will be raised and lowered, and engine driven means connected with said screws for actuating the same, said engine driven means comprising a worm shaft, worm and gear connection between said worm shaft and said screws, an engine carried by the said frame, a driving disk on the engine shaft, driven cones on said worm shaft meshing with said disk, operator controlled instrumentalities for moving said cones into and out of engagement with said disks for the purpose described.

VALLEY VIRGIL PEONE.
